CLAIM

The ornamental design for a toy boat, as shown and described.

DESCRIPTION

FIG. 1 is a front perspective view of a toy boat showing my new design;

FIG. 2 is a top plan view thereof shown on an enlarged scale;

FIG. 3 is a side elevational view thereof, the side opposite being substantially a mirror image;

FIG. 4 is a front elevational view thereof;

FIG. 5 is a rear elevational view thereof; and

FIG. 6 is a bottom plan view shown on an enlarged scale.

FIG. 1.

FIG. 2.

FIG. 4.

FIG. 5.

FIG. 6.
